The ornamental design for a bronchoscope, as shown and described.

DESCRIPTION

FIG. 1 is a left side elevational view of a bronchoscope according to the present invention.

FIG. 2 is a right side elevational view of the bronchoscope of FIG. 1.

FIG. 3 is a front elevational view of the bronchoscope of FIG. 1.

FIG. 4 is a rear elevational view of the bronchoscope of FIG. 1.

FIG. 5 is a top plan view of the bronchoscope of FIG. 1.

FIG. 6 is a bottom plan view of the bronchoscope of FIG. 1; and,

FIG. 7 is a perspective view of the bronchoscope of FIG. 1. The broken lines shown in the views are included for the purpose of illustrating portions of the endoscope that form no part of the claimed design.

The endoscope is shown with a symbolic break in its length. The appearance of any portion of the endoscope between the break lines forms no part of the claimed design.
